METHOD OF MAKING T'S

James Hall Taylor, Oak Park, Ill.

Application December 19, 1938, Serial No. 246,527

7 Claims. (Cl. 29—157)

This invention relates to pipe fittings, such as T's and analogous articles, and has to do with a method of making such articles.

My invention is directed to a method of making T's from tubular blanks, with expedition and facility, in such manner that extensive reforming of the blank to produce the T is avoided. More specifically, I provide a tubular cylindrical metal blank and reduce the end portions thereof in diameter and to concentricity with an axis extending through the blank eccentric thereto, while restraining against inward radial movement a limited area of the wall of the blank, at one side thereof, thus producing a partially formed T comprising a trunk or body portion having coaxial arms eccentric to the original blank and provided, at one side, with a protuberance, and then form this protuberance to a neck, completing the T. Further objects and advantages of my invention will appear from the detail description.

In the drawings:—

Figure 1 is an elevational view, partly broken away, showing semi-diagrammatically apparatus suitable for practicing the method of my invention and, in section, a blank from which a T is to be formed, this view being taken substantially on line 1—1 of Figure 2;

Figure 2 is a sectional view taken substantially on line 2—2 of Figure 1, certain parts being shown in elevation and certain other parts being broken away and shown in section;

Figure 3 is a view generally similar to Figure 2, illustrating the step of rolling down one end portion of the blank, the latter being shown in section;

Figure 4 is a view similar to Figure 3 but illustrating the step of rolling down the other end portion of the blank, the latter being shown partly broken away and in section;

Figure 5 is an end view of the partially formed T resulting from the operation of Figure 4;

Figure 6 is a sectional view of the partially formed T of Figures 4 and 5 and of apparatus for forming the protuberance of this partially formed T into a neck, certain parts being shown in elevation;

Figure 7 is a view similar to Figure 6 but illustrating the succeeding step of forming the neck of the T; and

Figure 8 is a central lengthwise sectional view through the T resulting from the neck forming operation of Figure 7.

In practicing the method of my invention any suitable apparatus may be employed. I have

illustrated, by way of example, and more or less semi-diagrammatically, one suitable form of apparatus. A disk 10 of suitable proportions is secured upon one end of a shaft 11, coaxial with the disk, this shaft being mounted for rotation in a journal member 12 and rotated in any suitable manner. A horn 13 is provided at one end with a coaxial stud 14 secured through disk 10, coaxially therewith, by means of two nuts 15 and 16 screwing upon stud 14, nut 15 bearing against the outer or rearward face of disk 10 and nut 16 constituting a jam nut. Shaft 11 is provided, in its forward end, with a recess 17 which accommodates the rearward portion of stud 14 and the nuts thereon. The axis of shaft 11, and consequently the common axis of rotation of disk 10 and horn 13, is indicated by the line x—x. A lug 18 formed integrally with horn 13, fits into a corresponding recess 19 in disk 10, assuring that the horn is retained in proper relation to the disk, for a purpose which will appear presently.

A ring member 20 is disposed at the forward face of disk 10, about horn 13, and is clamped between the disk and a circumferential flange 21 projecting from the horn. Ring member 20 is provided, in its outer face, with an inner annular groove 22 concentric with horn 13, and an outer annular groove 23 eccentric to groove 22 and merging into the latter at its lower portion, as will be clear from Figures 1 and 2. A pin 24, secured in ring member 20, extends into a corresponding recess in disk 10 and is effective for preventing turning of ring member 20 relative to disk 10 and horn 13. The axis of groove 23, indicated by the line y—y, is disposed above the axis of rotation x—x of disk 10 and the parts carried thereby, as will be clear from Figure 2.

Groove 23 is intended for reception of one end of a blank to be formed into a T, as will be described presently. The horn 13 is curved and extends radially of disk 10 toward the portion of groove 23 most remote from the axis x—x. The upper end of the horn is flat and is provided with a central tapered recess of squared cross-section which receives a correspondingly shaped shank 26 of a disk 27, having a flat inner face which seats upon the flat outer end of horn 13. The outer face 27a of disk 27 is rounded concentrically with axis y—y, conformably to the curvature of the inner face of the blank, above referred to, and is provided with a central outwardly projecting stud 28. Disk 27 cooperates with a clamping member 29 pivoted, at 30, upon the forward end of a pressure lever 31 rockably mounted, a short

distance from its inner end, upon a pin 32 extending between two ears 33 projecting from the forward face of disk 10. A pressure screw 34 is threaded through the outer end of lever 31 and bears at its rearward end, upon a pad or boss 35 formed integrally with disk 10 at the forward face thereof. A jam nut 36, threaded upon screw 34, provides means for securing the latter in adjustment.

10 The disk 10 and associated parts cooperate with a roller 38, mounted for rotation upon a shaft 39 appropriately mounted in a supporting structure 40, the latter being capable of movement perpendicular to axis $x-x$ and also having movement parallel with that axis.

15 In practicing the method of my invention, a cylindrical blank b , of tubular form and of wrought metal or other suitable material, is disposed with one end fitting into groove 23, the latter corresponding in diameter to the blank, as will be obvious. When the blank is disposed in this manner, disk 27 is at the midportion of the side of the blank more remote from axis $x-x$, and stud 28 fits in a corresponding opening o provided through that side of the blank, as shown in Figure 2, this stud being slightly less in extent radially of the blank than the wall thickness of the latter. When the blank b has been thus disposed, screw 34 is threaded through 20 arm 31, forcing member 29 toward disk 27, the latter and member 29 then cooperating to clamp between them a limited area of the wall of the blank b , it being noted that the clamping face of member 29 is concentric with the outer surface of disk 27, as shown in Figure 1. The blank b is thus secured to disk 10 and horn 13 for rotation therewith about axis $x-x$, extending through the blank eccentric thereto and nearer the lower side thereof, as viewed in Figure 2, 25 than the upper side, at which the forward end of horn 13 is disposed, stud 28 effectively preventing turning of the blank relative to the disk.

30 After the blank has thus been mounted upon the disk 10 and horn 13, it is rotated, by rotating shaft 11 and, during such rotation, is rolled down, at its end portion, to reduced diameter and to concentricity with axis $x-x$. Referring to Figure 3, this rolling down of the end portion of the blank is accomplished by moving the roller 38 inward of the blank radially thereof, as indicated by the arrow a , while also moving this roller lengthwise of the blank, as indicated by the arrow c . These movements may be imparted to the roller in any suitable known manner. The movement of roller 38 radially inward of the blank is such in extent that the end portion of the blank is rolled to an interior radius equal to the distance between the axis $x-x$ and the nearer side of the interior of the original blank. The horn 13 and disk 27 restrain the midportion of the blank, at the opposite side thereof, from inward radial movement, as will be obvious, the rolling of the end portion of the blank starting a short distance outward beyond disk 27, as shown in Figure 3. After one end of the blank has thus been rolled down, the blank is removed from horn 13 and replaced thereon in reversed position, with the rolled down end fitting into the groove 22, of the member 28, concentric with axis $x-x$, and the clamping member 29 is again moved into cooperating relation to the disk 27. The other end portion of the blank is then rolled down to reduced diameter and concentricity with the axis $x-x$, as in Figure 4. In that manner I provide a partially

formed T , shown in Figures 4 and 5, comprising a trunk or body b^1 having coaxial arms d , eccentric to the original blank, and provided, at one side, with a protuberance n^1 having therethrough the central opening o . The partially formed T of Figures 4 and 5 is then placed in a suitably recessed ring 43, with protuberance n^1 fitting into the upper end of a neck forming opening n^2 defined by ring 43. The latter seats in the recessed upper face of a supporting block 44, carried by uprights 45, this block having an opening 46 of greater diameter than and concentric with neck opening n^2 of ring 43. A pull rod 47, inserted through opening o of protuberance n^1 , has a former 48, of approximately inverted frustoconical shape, or other suitable shape, secured thereon within the partially formed T , by means of a nut 49 or in any other appropriate manner.

20 The maximum diameter of former 48 corresponds to the interior diameter of the neck of the desired T , the diameter of neck opening n^2 of ring 43 corresponding to the exterior diameter of neck of the desired T , as will be understood, and pull rod 47 is disposed coaxially with neck opening n^2 of ring 43. With the parts disposed as in Figure 6, pull rod 47 is moved downward, as indicated by the arrow p in Figure 7, in any suitable manner. In the downward movement of rod 47 former 48 expands the protuberance n^1 so as to form it, between former 48 and the surrounding wall of opening n^2 of ring 43, into the cylindrical neck n . That completes the T which is shown, in its completed form, in central lengthwise section in Figure 8.

25 When required, the blank from which the T is produced may be heated to proper working temperature, preliminary to rolling down each end portion thereof. In cases where the material of the blank is of such character as to render practicable rolling down of the end portions without heating the blank, the blank may be rolled cold. During the rolling operation, the roller 38 serves to displace and redistribute the metal of the end portion of the blank in such manner that the arms d of the finished blank are of uniform wall thickness, as shown in Figure 5 and as will be clear from Figures 6 to 8, inclusive. Due to the reduction in diameter of the end portions of the original blank, the completed T may, in certain cases, be of some what greater wall thickness, at the ends thereof, than the original blank. Ordinarily, however, the increase in wall thickness of the arms of the completed T is not appreciable, and has not been illustrated, for that reason.

30 Preferably, the end portions of the original blank are reduced by rolling, in the manner above described, since that is conducive to rapid reduction of the ends of the blank and to uniform distribution of the displaced metal, as has been noted. I contemplate, however, within the broader aspects of my invention, reducing the end portions of the blank in any other suitable manner, it being noted that an important feature of the method of my invention is the reduction in diameter of the end portions of the blank in such manner that the reduced end portions are concentric with an axis eccentric to the original blank, the interior radius of the reduced end portions being equal to the distance between such axis and the nearer side of the original blank, the neck of the T being formed from the protuberance remaining at the opposite side of the blank, whereby extensive reform-

ing of the original blank, to produce the finished T, is obviated.

I claim:—

1. The method of making a T, which comprises 5 rotating a tubular cylindrical metal blank about an eccentric axis extending through and nearer one side of the blank than the opposite side thereof, rolling down the end portions of the blank to concentricity with such eccentric axis and to an interior radius equal to the distance between said axis and said nearer side of the blank, by a roller moving radially inward of said blank with relative movement between said roller and blank lengthwise of the latter, while restraining the 10 midportion of the opposite side of said blank against inward movement, thereby producing a partially formed T having a body with arms of less diameter than the original blank and a protuberance at the opposite side of the body between the arms, and completing the T by forming the protuberance into a neck.

2. The method of making a T from a tubular cylindrical metal blank, which comprises securing the blank over a member disposed at the midportion of one side of the blank effective for restraining radial inward movement of a corresponding area of the wall of the blank, rotating the blank about an eccentric axis extending therethrough and nearer the opposite side than said one side 30 of the blank, rolling down the end portions of the blank beyond said area to concentricity with such eccentric axis and to an interior radius equal to the distance between said axis and said nearer side of the blank, by a roller moving radially inward of said blank with relative movement between said roller and blank lengthwise of the latter, thereby producing a partially formed T having a body with arms of less diameter than the original blank and a protuberance at the opposite side of the body between the arms, and completing the T by forming the protuberance into a neck.

3. The method of making a T from a tubular cylindrical metal blank, which comprises restraining against inward radial movement a limited area of the wall of the blank at the midportion of one side thereof, rotating the blank about an eccentric axis extending therethrough and nearer the opposite side than said one side of the blank, rolling down the end portions of the blank beyond said area to concentricity with such eccentric axis and to an interior radius equal to the distance between said axis and said nearer side of the blank, by a roller moving radially inward of said blank with relative movement between said roller and blank lengthwise of the latter, thereby producing a partially formed T having a body with arms of less diameter than the original blank and a protuberance at the opposite side of the body between the arms, and completing the T by forming the protuberance into a neck.

4. The method of making a T from a tubular cylindrical metal blank, which comprises restraining against inward radial movement a limited area of the wall of the blank at the midportion of one side thereof, reducing the end portions of the blank beyond said area to concentricity with an eccentric axis extending therethrough nearer the opposite side than said one

side thereof and to an interior radius equal to the distance between such axis and the nearer side thereto of the original blank, thereby producing a partially formed T having a body with arms of less diameter than the original blank and a protuberance at the opposite side of the body between the arms, and completing the T by forming the protuberance into a neck.

5. The method of making a T from a tubular cylindrical metal blank, which comprises restraining against inward radial movement a limited area of the wall of the blank at the midportion of one side thereof, rolling down the end portions of the blank beyond said area to reduced diameter and concentricity with an axis 15 eccentric to the blank extending therethrough nearer the opposite side thereof than said one side, thereby producing a partially formed T having a body with arms of less diameter than the original blank and a protuberance at the opposite 20 side of the body between the arms, and completing the T by forming the protuberance into a neck.

6. The method of making a T from a tubular cylindrical metal blank, which comprises mounting the blank upon a member rotatable about an axis extending through the blank eccentric thereto and nearer one side than the opposite side of the blank, with a curved horn secured at one end to said member coaxially therewith extending into the blank and having its other end at 30 the midportion of the opposite side of the blank and provided with a stud fitting in a corresponding opening in the blank wall, rotating said member and blank and rolling down one end portion of the blank to reduced diameter and concentricity with the axis of rotation of said member, reversing the blank and rolling down the other end portion thereof similarly to said one end portion, thereby producing a partially formed T having a body with arms of less diameter than the 40 original blank and a protuberance at the opposite side of the body between the arms, and completing the T by forming the protuberance into a neck.

7. The method of making a T from a tubular cylindrical metal blank, which comprises mounting the blank upon a member rotatable about an axis extending through the blank eccentric thereto and nearer one side than the opposite side of the blank, with a curved horn secured at one end to said member coaxially therewith extending 50 into the blank and having its other end at the midportion of the opposite side of the blank and provided with a stud fitting in a corresponding opening in the blank wall, clamping a limited area of said opposite wall between said other end of 55 said horn and a cooperating exterior clamping member carried by said rotatable member, rotating said latter member and blank and rolling down one end portion of the blank to reduced diameter and concentricity with the axis of rotation of said rotatable member, reversing the blank and rolling down the other end portion thereof similarly to said one end portion, thereby producing a partially formed T having a body with arms of less diameter than the original blank 65 and a protuberance at the opposite side of the body between the arms, and completing the T by forming the protuberance into a neck.

JAMES HALL TAYLOR.
